[57] CLAIM

The ornamental design for a trash bin with multiple liner, as shown and described.

DESCRIPTION

FIG. 1 is a front elevational view of a trash bin with multiple liner showing our new design;

FIG. 2 is a rear elevational view thereof;

FIG. 3 is a side elevational view thereof, the opposite side elevational view being a mirror image of that shown;

FIG. 4 is a cross-sectional view taken along line 4 of FIG. 5;

FIG. 5 is a top plan view thereof;

FIG. 6 is a bottom plan view thereof; and,

FIG. 7 is a front, top perspective view thereof.
